CLAIM

The ornamental design for a floor lamp, as shown and described.

DESCRIPTION

FIG. 1 is a front perspective view of a floor lamp showing my new design;

FIG. 2 is a front elevational view thereof;

FIG. 3 is a rear elevational view thereof;

FIG. 4 is a side elevational view thereof, the opposite side being a mirror image;

FIG. 5 is a top plan view thereof on an enlarged scale;

FIG. 6 is a bottom plan view thereof on an enlarged scale;

FIG. 7 is a fragmentary front perspective view of a second embodiment of my new design, the supporting stand being omitted for convenience of illustration;

FIG. 8 is a fragmentary rear elevational view thereof; and,

FIG. 9 is a fragmentary side elevational view thereof, the opposite side being a mirror image.

The second embodiment of the design as shown in FIGS. 7, 8, and 9 differs from the first embodiment only in the configuration of the knobs on the lower pivot adjacent the stand.
